INVENTORS.
WILLIAM A. NIMMER
BY JOHN F. PILGRIM

Geo. P. Kimmel. ATTORNEY

UNITED STATES PATENT OFFICE.

JOHN F. PILGRIM AND WILLIAM A. NIMMER, OF TWO RIVERS, WISCONSIN.

MAP-CASE.

1,397,327.

Specification of Letters Patent.

Patented Nov. 15, 1921.

Application filed April 7, 1921. Serial No. 459,364.

To all whom it may concern:

Be it known that we, JOHN F. PILGRIM and WILLIAM A. NIMMER, citizens of the United States, residing at Two Rivers, in the 5 county of Manitowoc and State of Wisconsin, have invented certain new and useful Improvements in Map-Cases, of which the following is a specification.

This invention relates to holders for maps, 10 charts or other articles of display and more particularly to that type of holder designed to accommodate and receive a plurality of rollers and permit the same to be operated whereby the map, chart, or other article may 15 be withdrawn from said holder for inspection and returned.

The primary object of the invention resides in the construction of a holder for receiving a plurality of spring rollers therein 20 and which may be mounted on a support or attached to a wall for instance in such position as to enable one to operate any one of said rollers to withdraw the map or other article rolled thereon including means for 25 maintaining the roller supporting drum stationary when any one of the rollers is operated.

Another and very important object of the invention resides in the construction of a 30 simple, yet practical and highly efficient type of holder for maps, charts or articles of display whereby the same may be easily and quickly drawn out of the holder for exhibition and readily returned, and which 35 will permit any desired map or article to be drawn out and exhibited and subsequently returned to permit another roller to be operated for a like purpose including spring controlled means for maintaining the roller supporting members stationary.

A further and continued object of the invention resides in the construction of a novel and improved holder of the type above set forth, which is extremely simple in construction, consisting of comparatively few parts therefor, inexpensive to manufacture, highly efficient in operation, practical in use, easily operable, durable in construction and capable of universal use in connection with 50 various articles of display for commercial or exhibition purposes.

With these and other objects in view as will appear as the description proceeds, the invention comprises the novel features of

construction, accompanied by elements and 55 arrangements of parts which will be more fully described in the following specification and set forth with particularity in the subject matter being claimed and appended thereto, wherein:—

Figure 1 is an end elevation showing the hinged closure for the holder.

Fig. 2 is a front view thereof shown partly in section.

Fig. 3 is a view partly in section of a 65 spring roller.

Fig. 4 is an end view of one of the roller carrying drums.

Referring now to the drawings wherein like parts refer to similar parts throughout 70 the specification, 5 designates a rectangular casing or holder, preferably constructed of wood or similar material and adapted to be attached to a wall or supported by suitable brackets (not shown), said casing or holder 75 being provided with a bottom closure or cover 6 which is hinged as at 7 to its lower rear side whereby ready access may be had to the interior as is readily understood.

Supporting brackets 8, 9 secured interiorly 80 of the casing or holder and to the respective ends of the same, carry the end bearings 10 in which are rotatably mounted the roller supporting heads 11, 12 which carry the map, chart, or article to be exhibited as 85 clearly shown by Fig. 2 of the drawing.

The end spindles 13 which extend through the roller supporting heads 11 and 12 and are retained in the bearing above referred to, permit the said heads to rotate in either 90 direction for conveniently bringing any one of the rollers subsequently to be referred to in position so that the article carried thereby may be withdrawn and exhibited.

The end heads 11 and 12 are of course provided with a plurality of apertures or bearings 14 spaced equidistant and near the periphery of the same for receiving the end spindles 15, 16 of a spring roller designated in its entirety by numeral 17. Each of the 100 spring rollers 17 have wound thereon the map, chart or other article to be displayed, the ends of said rollers being provided with the usual ratchet and dog mechanism 18, 19 in the ends of the roller.

The end head 12 is provided with a ratchet 20 on its outer face, the teeth 21 of which are adapted to coöperate with the hooked end 22

of a pivoted lever 23, said lever being of course pivoted at 24 to the casing 5 and has connected at its outer end a flexible chain 26 provided with a ring 27 for operating said lever, the hooked end 22 of which is normally depressed by a flat spring 28 also secured to the casing and which prevents the head 12 from rotating under normal conditions.

10 By this construction, it will be readily seen that as the flexible chain depresses the lever 23 and raises the hooked end 22 from one of the teeth of the ratchet wheel, the end roller supporting heads 11 and 12 may be rotated to bring the desired spring roller 17 to a position whereby the article carried thereby may be withdrawn from the casing and exhibited as is well understood.

15 In the accompanying drawings, we have illustrated our invention embodied in one form by way of example, and which in practice has been found to be highly satisfactory in obtaining the desired results. It will be obvious however that other embodiments 20 may be adopted and that various changes in the details of construction may be resorted to by those skilled in the art without departing from the spirit and scope of the invention. It is furthermore understood 25 that the invention is not necessarily limited or restricted to the precise elements shown except in so far as such limitations are 30 specified in the subject matter being claimed.

Having shown and described our inven-

tion, what we now claim as new and desire 35 to secure by Letters Patent of the United States is:—

1. A device of the class described comprising a rectangular casing having a hinged bottom, roller supporting heads having end 40 spindles journaled in the sides of the casing, a plurality of equally spaced spring rollers rotatably mounted near the peripheral edge of said head within said casing, a ratchet on one of said heads and spring controlled 45 locking means attached to the casing co-operating with said ratchet to prevent rotation of the heads when moved to a selective position.

2. A device of the class described comprising a rectangular, closed casing having a hinged bottom, bearings carried by the ends and within said casing, roller supporting heads journaled in said bearings and having a plurality of equally spaced spring rollers 55 rotatably mounted near the peripheral edge of said heads and operable in either direction, a ratchet on one of said heads and rotatable therewith, a spring controlled locking lever pivotally secured to the casing and 60 co-operating with the ratchet and a flexible chain for releasing said locking means to permit rotation of said heads to move a selective spring roller to operative position.

In testimony whereof, we affix our signatures hereto.

JOHN F. PILGRIM.

WILLIAM A. NIMMER.
